UNITED STATES PATENT OFFICE.

HERMANN KOEPLINGER, OF VIENNA, AUSTRIA-HUNGARY.

DEVICE FOR PERFORATING FIGURED IRON.

989,159.

Specification of Letters Patent. Patented Apr. 11, 1911.

Application filed June 27, 1910. Serial No. 568,954.

To all whom it may concern:

Be it known that I, HERMANN KOEPLINGER, a subject of the Emperor of Austria-Hungary, and a resident of Herklotzgasse 23, Vienna, XV, in the Empire of Austria-Hungary, have invented a Device for Perforating Figured Iron; and I do hereby declare the following to be a full, clear, and exact description of the invention, such as will enable others skilled in the art to which it appertains to make and use the same.

My invention relates to devices for perforating figured iron for making the cross-work of windows.

When making known window cross-work of figured iron it is necessary to provide the cross-bars with holes which enable the passage of the crossing stay-bars. In general, the figured iron employed is of T-shaped section, so that for making the hole it is necessary to bend the flange and to punch an aperture in the web.

According to my invention, the flange is bent by a new kind of tool which is guided rectilinearly in the direction of the flange and is of gradually increasing cross-section similar to the bend which is to be made.

Some illustrative embodiments of my invention are represented by way of example in the accompanying drawing, wherein:

Figures 1 and 2 are vertical sectional elevation, and top plan view, respectively, showing one form of my apparatus comprising the new kind of tool, while Figs. 3 to 5 show a modified form of my apparatus comprising a modified form of tool, Fig. 3 being a vertical sectional elevation, Fig. 4 a top plan view and Fig. 5 a perspective view.

Referring firstly to Figs. 1 and 2, the tool 1 is guided rectilinearly on the one hand in its holder, not shown, and on the other hand in the swage 2, while the piece of work 3 is supported in the swage at the two sides of the bend 4 which is to be made. As will be understood from the drawing, the tool is guided at the face 5 of the swage before it acts on the piece of work, this arrangement having the purpose of preventing the tool being subjected to prejudicial bending strains and assuring that the flange is separated directly at the joint between the flange and the web. When the tool is forced downward all the various sections of the same act in order and consequently en-

large the aperture made by the point of the tool and bend the flange.

An important advantage obtained by employing my new apparatus comprising the new tool consists in the direction of motion for the bending of the flange coinciding with the tools acting like punches on the web, so that such can be connected directly to the tool. For example, if a window-bar is to be worked according to a process, in which it is necessary, for making the aperture through which the bar is to be pushed, to punch a trapezoidal hole in the web, then to bend the flange and finally to punch a longitudinal aperture connected to the trapezoidal aperture, I may employ the apparatus which is represented in Figs. 3 to 5 and admits of the manufacture in one single operation. Referring to these figures, the tool has a trapezoidal section at its bottom end 6 and enables a trapezoidal hole to be made in the web when a suitable swage is employed. The conical part 7 of the tool adjoining the trapezoidal end 6 serves for making the bend, its section being similar to the bend 80 and gradually increasing in size.

It is preferable to avoid sharp edges on the part 7 and to calibrate the bend by a prismatic part 8 which is connected with the part 7 and cooperates with the suitably-shaped swage 9. The top end 10 of the tool has a section like the aperture which is to be made, so that the hole connected with the trapezium can be made by this part. For successful operation, it is necessary, in this case also, to support the tool as soon as the part causing the bend operates. For this purpose, the hole which the part 6 of the tool makes is trapezoidal, so that this part can be supported at the faces 11 of the swage. Further, it is essential to make the part 6 sufficiently long in order that the tool may be guided in the swage under the recess 12, which passes through the latter and holds the web of the tool, as soon as the conical part 7 acts on the part of the flange opposite the recess 12.

Owing to the friction occurring when making the bend, the flange is exposed in the direction of the movement of the tool to bending strains which tends to deform the bent part. According to my invention this is prevented by special means on the swage. These means consist of a displaceable plate 13, which supports the part which is to be

bent at any time, and is pressed by a spring 14 against the tool and shifted by the conical part of the tool in proportion as the bending proceeds.

5 As seen from Fig. 5, the part 9^a of the swage which receives the flange of the piece of work is displaceable along a dovetail guide and is held in the operative position by a wedge 15 which can be turned. The 10 part 9^a must be displaceable in order to be able to remove from the swage the piece of work after it has been bent.

What I claim as my invention and desire to secure by Letters Patent is:

15 1. In means for making apertures in flanged figured iron, a tool guided rectilinearly in the direction of the flange, the section of the tool being similar to the bend to be made in the flange and having a long sharp taper extending to its acting or entering end, substantially as described.

20 2. In means for making apertures in flanged figured iron, a tool guided rectilinearly in the direction of the flange, the section of the tool being similar to the bend to be made in the flange and having a long sharp taper extending to its acting or entering end, and punching parts arranged on said tool, substantially as described.

25 3. In means for making apertures in flanged figured iron, a tool formed as a punch at its bottom end and guided rectilinearly in the direction of the flange, the section of the tool being similar to the bend to be made in the flange and having a long sharp taper extending to its acting or entering end, substantially as described.

35

4. In means for making apertures in flanged figured iron, a tool guided rectilinearly in the direction of the flange and having a section similar to the bend to be made in the flange and having a long sharp taper extending to its acting or entering end, a punching part on the bottom end of said tool and a punching part at one side of the upper part of said tool, substantially as described.

40 5. In means for making apertures in flanged figured iron, the combination with a swage for holding the figured iron of a tool guided rectilinearly by the swage in the direction of the flange of the figured iron, the section of the tool being similar to the bend to be made in the flange and gradually increasing in size, substantially as described.

45 6. In means for making apertures in flanged figured iron, the combination with a swage comprising a fixed part and a spring-pressed movable part for holding the figured iron with the flange abutting against the movable part, of a tool guided rectilinearly by the swage in the direction of the flange of the figured iron, the section of the tool being similar to the bend to be made in the flange and gradually increasing in size, substantially as described.

50 In testimony whereof I have signed my name to this specification in the presence of two subscribing witnesses.

HERMANN KOEPLINGER.
